(57) **CLAIM**

I claim the ornamental design for a bottle, as shown and described.

DESCRIPTION

FIG. 1 is a top perspective view of a bottle showing my new design;

FIG. 2 is a bottom perspective view thereof;

FIG. 3 is a front elevation view thereof, the rear elevation view being identical; and,

FIG. 4 is a top plan view thereof.

The dot-dash broken line(s) define the bounds of the claim and form no part thereof.
